UNITED STATES PATENT OFFICE.

JOHN R. WHARRY, OF MOUNDSVILLE, WEST VIRGINIA, ASSIGNOR OF ONE-HALF TO WINFIELD S. FREED, OF SAME PLACE.

VEGETABLE-SLICER.

SPECIFICATION forming part of Letters Patent No. 340,843, dated April 27, 1886.

Application filed February 17, 1886. Serial No. 192,259. (No model.)

To all whom it may concern:

Be it known that I, JOHN R. WHARRY, of Moundsville, in the county of Marshall and State of West Virginia, have invented certain new and useful Improvements in Vegetable-Slicers; and I do hereby declare the following to be a full, clear, and exact description of the invention, such as will enable others skilled in the art to which it pertains to make and use it, reference being had to the accompanying drawings, which form part of this specification.

My invention relates to an improvement in vegetable and fruit slicing machines; and it consists in, first, the combination of the frame-work, the knife, the bottom pieces, means for moving these pieces, and the box which is moved back and forth over the knife, with the pivotal plates, which are provided with pivots at their upper ends; second, the combination of the frame-work, the knife, the bottom pieces, means for moving these pieces, and the box which is moved back and forth over the knife, with the pivotal plates, which are provided with pivots at their upper ends and the turned-out flanges at their lower ends; third, the combination of the frame-work, the pivoted bottom pieces, the grooved cross-pieces, and the cams, which have their edges to catch in the cross-pieces, so as to give the bottom pieces a positive movement up and down; fourth, the combination, with the frame-work, the pivoted bottom pieces, the knife, the cross-pieces provided with inclined grooves, and the cams provided with inclined flanges and stops, all of which will be more fully described hereinafter.

Figure 1 is a vertical section of a slicing-machine embodying my invention. Fig. 2 is an inverted view. Fig. 3 is a detail view of the pivot-iron. Fig. 4 is a perspective of a presser-board.

A represents the frame-work, which may be either of the construction here shown or any other that may be preferred. This frame-work is intended to be clamped to a table or any other suitable support which is provided for it. The knife B is secured diagonally across the top of the frame, in the usual manner, and is made sharp at both of its edges, so as to cut upon both edges alike. The two bottom pieces,

C, are pivoted at their outer ends upon the pivotal plates or castings D, while their inner ends are raised and lowered by means of the cams under the free ends of the pieces C, as shown. These pivotal plates have their lower corners, F, turned outward, so as to catch under the lower edge of the frame A, and have the pivotal points G formed upon the inner sides of their upper ends. The turned-out points serve as gages, so as to enable the plates to be placed in position without any measurements being taken or any trouble to get them into their positions. It is only necessary to place the outer edges of the plates against the end pieces and have the flanges F catch against the under side of the side pieces, when they will be in a proper position to receive the bottom pieces between them when the frame-work is put together. The pivotal holes in the outer ends of the bottom pieces have only to be made, and then the bottom pieces are ready to be secured in position.

Secured across the frame-work, on its under side, are two diagonal cross-pieces, H, which have inclined grooves I formed in their outer sides for the flanges J of the cams L to catch in.

Pivoted to the under side of each one of the bottom pieces is a cam, L, which may either be tubular in shape, as here shown, or any other that may be preferred, and which may have the inclined flanges J, formed either partially around their lower edges, or entirely around them, as may be preferred. When the cams are formed as here shown, there is a stop, N, formed at one end of the flange, and another one, O, formed upon the lower edge of the tubular portion, for the purpose of preventing the cams from being turned beyond a certain point in either direction. The flanges J catch in the grooves in the cross-pieces, and thus move the free end of the bottom pieces up and down. By having these flanges catch in the diagonal grooves a positive vertical adjustment can be given to the bottom pieces in relation to the knife, whenever so desired.

The upper portion of the frame-work is grooved so as to receive the sliding-box Q, which is also grooved at its lower edges, so as to correspond with the grooves in the frame. To one end of this box is secured the handle

R, by means of which it is moved back and forth upon the frame-work for the purpose of moving the fruit and vegetables which are to be sliced back and forth over the two edges 5 of the knife. In this box is placed a presser-board, R', to the upper side of which is connected the vertical follower portion S, which is provided with the two arms T, which catch over the outer sides of the box in suitable 10 grooves prepared for them, and thus hold the presser-board always in a horizontal position. The weight of the presser-board keeps the fruit and vegetables which are to be sliced pressed downward upon the knife, so that it is always 15 fed forward ready to be sliced, no matter in which direction the box is moved.

Having thus described my invention, I claim—

1. The combination of the frame-work, the 20 knife, the bottom pieces, means for moving these pieces, and the box, which is moved back and forth over the knife, with the pivotal plates, which are provided with the pivots at their upper ends, substantially as shown.

2. The combination of the frame-work, the 25 knife, the bottom pieces, means for moving these pieces, and the box, which is moved back and forth over the knife, with the pivotal plates, which are provided with pivots at their upper ends and the turned-out flanges at their 30 lower ends, substantially as described.

3. The combination of the frame-work, the pivoted bottom pieces, the grooved cross-pieces, and the cams, which have their edges to catch in the grooves of the cross-pieces, so 35 as to give the bottom pieces a positive movement up and down, substantially as set forth.

4. The combination of the frame-work, the pivoted bottom pieces, the knife, the cross-pieces provided with inclined grooves, and 40 the cams provided with inclined flanges and stops, substantially as specified.

In testimony whereof I affix my signature in presence of two witnesses.

JOHN R. WHARRY.
